Patented Feb. 10, 1920.

FIG. 1.

FIG. 2.

FIG. 3.

FIG. 4.

INVENTOR:
Lawrence A. Heinle,
By Monroe Hall, Atty.

UNITED STATES PATENT OFFICE.

LAWRENCE A. HEINLE, OF TOLEDO, OHIO.

HEAT-INSULATED CONTAINER.

1,330,704.

Specification of Letters Patent. Patented Feb. 10, 1920.

Application filed April 24, 1919. Serial No. 292,250.

To all whom it may concern:

Be it known that I, LAWRENCE A. HEINLE, a citizen of the United States, residing at Toledo, in the county of Lucas and State 5 of Ohio, have invented certain new and useful Improvements in Heat-Insulated Containers; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to and is intended to provide a container for the temporary storage and the transportation of such articles of food as become injured or spoiled by exposure to warm atmosphere, including 20 such articles as ice-cream, butter, oysters and many other foods. My container is adapted also for the reception and transportation of articles designed to remain heated for a limited period.

25 While the advantages of liquid containers of the "thermos" or vacuum type are well understood, the high non-conductivity of a partial vacuum in the annular space between two concentric closed vessels has not heretofore been successfully utilized in connection 30 with articles such as are above indicated. This has been due largely to the limited size of the bottles, their contracted mouths,—adapted only for pouring,—and to the fragile character of the material employed.

35 In carrying out my invention, to obviate the difficulties indicated, I avail myself of the advantages of the vacuum principle alluded to, and provide co-axial vessels of 40 non-fragile character, so protected by a substantial non-heat conducting casing that they will not be injured by ordinary use. The mouth of my container flares outwardly affording ready access to its interior. The 45 necessarily large closure for the flaring mouth is hollow and exhausted of air.

With these and other ends in view, my container consists of the devices, construction and arrangement of parts hereinafter 50 described, and illustrated in the accompanying drawings in which—

55 Figure 1 is a top-plan view of my container removed from its case; Fig. 2, a central vertical sectional elevation of the same in position in its case; Fig. 3, a perspective view, on an enlarged scale, of certain details

of construction hereinafter referred to, and Fig. 4, a like view of certain other details hereinafter referred to.

Like numerals indicate like parts throughout the drawings.

In the drawings, 1 is an inner vessel and 2 an outer vessel, the two vessels and their casing, hereinafter referred to, being, preferably, cylindrical, though other shapes may 60 be employed. These vessels, 1 and 2, are composed of sheet metal, preferably sheet iron or sheet steel, vitreously enameled or glazed, as at 1^a—2^a, inside and outside, after the manner of the familiar "granite-ware" 70 culinary vessels. The glaze does not, however, extend quite to the upper edges of the two vessels, there being left, unglazed, two upwardly projecting flange-portions 1^b and 2^b. These two flange-portions, after the two 75 vessels are separately glazed, are welded together, as plainly indicated in Figs. 3 and 4. The two vessels now constitute practically one piece, there being between the inner and outer walls a hermetically sealed 80 annular space 3. From this space the air is exhausted, for instance at the point indicated at 4, in the usual or any preferred manner.

Near its upper end the vessel 1 flares 85 slightly outwardly, as at 5, and then turns horizontally outwardly, as at 6, and then turns upwardly to form the welded flange-portion 1^b. It will now be seen that the impervious inner and outer vessels 1 and 2 are 90 rigidly and permanently secured together and against relative movement.

7 is the lid of my container. It is composed of two pieces of sheet metal like that of the parts 1 and 2. The top piece 8 is 95 pressed, stamped, or otherwise formed as an inverted pan, having an extended horizontal flange 9. The lower part of the lid 10 is also shaped as a pan, having an extended horizontal flange 11. The upper and lower 100 pieces are separately glazed or enameled on both sides, except the flanges 9—11. These two flanges are welded together. Now the lid constitutes a stout impervious hermetically sealed hollow body from which the air 105 may be exhausted, as at 12, in the usual or any preferred manner. The side of the lower member of the lid is inclined to conform to the slant 5 of the vessel 1, but these two surfaces are prevented from contact by 110 an interposed gasket 13, of any suitable cork-like material, which gasket also pre-

vents the flange of the lid from contacting with the shoulder formed by the part 6.

The flange of the lid 8, which fits around the inside of the upstanding flange 1^b, is 5 hinged at one side, as at 14, to the flange-portion 1^b—2^b. At its opposite side the lid is pressed tightly down into position and is there detachably held by a clamp 15.

16 is a case designed to receive the above 10 described container with a fit just close enough to permit its convenient reception and withdrawal. This case consists of inner and outer concentric walls—preferably sheet metal—spaced apart to form an annular 15 space in which is packed, as at 17, some non-heat-conducting material such, for instance, as asbestos. A lid or cover 18 is hinged, as at 19, to one side of the top of the case, the opposite side of the lid being provided with 20 a suitable fastening device, in this case, for illustration, a spring catch 20.

Having described my invention, what I claim and desire to secure by Letters Patent is—

25 1. In a container of the described character, two co-axial sheet metal vessels having therebetween an exhausted annular space, said vessels being vitreously enameled on their adjacent faces, said vessels having 30 at one end unenameled marginal flanges which are welded together.

2. A container of the described character, comprising two co-axial sheet metal vessels having therebetween an exhausted annular 35 space, said vessels being exteriorly and interiorly vitreously enameled, said vessels, at one end, having extended unenameled flanges which are hermetically sealed together.

40 3. In a container of the described character, two co-axial sheet metal vessels having therebetween an exhausted annular space,

said vessels being exteriorly and interiorly vitreously enameled, said vessels having at one end unglazed flange-portions which are 45 welded together, the inner vessel having an outwardly flaring mouth, a closure for said mouth comprising a hollow exhausted member which conforms to said flaring mouth, and a gasket forming a seat for said closure. 50

4. In a container of the described character, two vitreously enameled co-axial sheet metal vessels having therebetween an exhausted annular space, said vessels, at one 55 end, having extended unenameled flanges which are hermetically sealed together, a closure for said vessel consisting of a hollow member, hinged connections between said closure and said extended flanges, and 60 devices for securing said closure in closed relation.

5. A container of the described character, comprising two co-axial sheet metal vessels having therebetween an exhausted annular space, said vessels being vitreously enameled, said vessels having, at one end, unenameled flanges which are hermetically sealed together, the inner vessel having an outwardly flaring mouth, a closure for said mouth comprising a hollow, exhausted member which conforms to said flaring mouth, and devices for securing said closure in closed relation, in combination with a suitable receptacle for said container, which receptacle conforms to and protects the enamel of the outer wall and the closure of said container. 70 75

In testimony whereof I affix my signature in presence of two witnesses.

LAWRENCE A. HEINLE.
